United States Patent Office

Des. 189,745
Patented Feb. 14, 1961

189,745

MOTOR VEHICLE

Hermann H. Fr. Ahrens, Stuttgart-Vaihingen, and Joachim Clasen, Stuttgart, Germany, assignors to Daimler-Benz Aktiengesellschaft, Stuttgart-Unterturkheim, Germany

Filed Mar. 10, 1960, Ser. No. 59,687

Claims priority, application Germany Sept. 11, 1959

Term of patent 7 years

(Cl. D14—3)

FIG. 1

Des. 189,745

PAGE 2

FIG. 2

FIG. 3

FIG. 4

Figure 1 is a front perspective showing the front and left side of the vehicle;

Figure 2 is a rear perspective showing the rear and right side of the vehicle;

Figure 3 is a left side elevation; and

Figure 4 is a right side elevation.

The broken lines indicate portions of the motor vehicle visible through the windows and windshield.

We claim:

The ornamental design for a motor vehicle, substantially as shown and described.

References Cited in the file of this patent

UNITED STATES PATENTS

D. 180,312 Ahrens ----- May 21, 1957